DOOR DRIVING MECHANISM

Joseph A. Langer, 941 Geary St., San Francisco, Calif.
Filed Dec. 19, 1962, Ser. No. 245,725
6 Claims. (Cl. 160—133)

This invention relates to vertically opening or rolling type doors for buildings, and more particularly it relates to an improved barrel drive mechanism for such doors.

As commonly referred to in the building industry a rolling type door is one composed of a series of connected pieces which give it a flexibility in one dimension and enable it to be lifted vertically by either winding it up on a roller like a window shade or by moving it along tracks into a stowed position. Such doors are particularly adaptable in buildings having large door openings for accommodating freight handling vehicles or for service or garage facilities. In smaller buildings including private dwellings, such doors are particularly suitable as garage closures. Since in many installations rolling doors are made of relatively heavy durable material and are large so as to cover an extensive opening, such doors are usually heavy, and a considerable amount of power is required to manipulate them from the closed to the open position. In some rolling door constructions heretofore devised, a complicated and expensive reduction gear mechanism was utilized to provide the power necessary to rotate the barrel and thus wind up the door. In my Patent Number 2,540,742, I was able to eliminate the need for a reduction gear mechanism by utilizing a coiled spring mechanism within the barrel for lifting the door and winding it around the barrel when opening the door. While this arrangement provided the necessary power in many rolling door installations it had several inherent disadvantages which now have been overcome by the present invention.

One major object of the present invention is to provide an improved rolling door drive mechanism that will provide increased power and smoother operation for doors of greater size.

Another object of the invention is to provide a driving mechanism well adapted for operating vertically lifting doors of several different types.

A further object of the present invention is to provide a rolling door mechanism that will eliminate any binding and will reduce friction between components within the barrel, thereby making the door easy to control with a minimum of effort during its opening and closing. With my invention the winding barrel mechanism provides a steady torsional force during the entire travel of the door that results in remarkably smooth operation.

Still another object of my invention is to provide an improved rolling door mechanism with fewer parts that can be arranged in a more compact package, and which is more durable.

Another object of my invention is to provide a rolling door mechanism that is particularly well adapted for ease and economy of manufacture.

A further object of the present invention is to provide a rolling door mechanism wherein the wind-up power for the flexible door can be readily adjusted with initial torsional energy to obtain the desired operating characteristics.

The foregoing and other important objects of my invention are accomplished by a driving barrel mechanism which, broadly considered, comprises a series of nested torque tubes supported within the barrel housing and connected at alternate ends. The innermost tube extending outside the barrel is restrained in a fixed position and the outermost tube is fixed internally to one end of the barrel, so that rotation of the barrel causes the

2

tubes to twist and store or release torsional energy when the door is operated. When the door is being lowered its weight helps to rotate the barrel in "winding-up" the torque tubes, whereas when the door is to be opened by raising it, the stored torsional energy is released to overcome the door weight and any mechanical friction.

Other objects, advantages and features of my invention will become apparent from the following detailed description and from the drawing, in which:

10 FIG. 1 is a view in front elevation of a typical flexible door installation according to the invention with portions of the door removed to conserve space;

15 FIG. 2 is an enlarged view in elevation and in section showing the internal details of a barrel mechanism embodying principles of the invention with a central portion removed to conserve space;

FIG. 3 is a view in section taken along the line 3—3 of FIG. 2;

20 FIG. 4 is a view in section taken along the line 4—4 of FIG. 2;

FIG. 5 is an enlarged view in elevation and in section showing the internal details of a modified form of barrel mechanism in accordance with the invention;

25 FIG. 6 is a fragmentary view in front elevation of a barrel mechanism according to the invention in combination with a sliding type door;

FIG. 7 is a view in side elevation and in section taken along line 7—7 of FIG. 6;

30 FIG. 8 is an enlarged fragmentary view in section taken along line 8—8 of FIG. 7.

Referring to the drawing, FIG. 1 shows a typical lifting rolling type door installation having a barrel drive mechanism 10 embodying the principles of the invention. The door 11 is affixed to the outer surface of a barrel 12 which is an elongated tubular member. The barrel is held in place above the doorway 13 and attached to the wall 14 of the building by some appropriate means such as a pair of support brackets 15. The brackets 15 may be provided with an inner race of ball bearings so that barrel 12 can rotate freely during its operation. To one end of the barrel 12 is rigidly attached a star or gear wheel 17 or some equivalent device by a control chain 18 that hangs downward at one side of the doorway 13. As the chain 18 is pulled, the gear wheel 17 rotates the barrel in the proper direction and causes the door 11 to be raised or lowered.

50 In accordance with the invention, the barrel drive mechanism 10 as shown in detail in FIG. 2, continuously supplies the necessary torsional power so that the door 11 will operate smoothly with a minimum of effort. This torsional power within the barrel 12 is provided by a torsion spring 19 comprising a series of interconnected coaxial torque tubes. The tubes are connected consecutively to each other and to the barrel 12 in a unique manner so that their equivalent operating length is much greater than the barrel itself.

55 In the embodiment of FIG. 2, the barrel casing 12 is provided with a pair of hub members 21 and 22 that are affixed rigidly to its opposite ends. On its outer end surface the hub member 21 is rigidly attached to the gear wheel 17 by means of a flanged fitting 23. Extending axially inwardly the inner end surface 24 of the hub 21 within the barrel 12 is a cylindrical cavity 25 that forms a bearing support or journal for one end of the coaxial torsion spring 19. A suitable bushing or bearing 26 is installed within the cavity 25.

60 At the opposite end of the barrel casing 12 the hub member 22 has a central bore 27 which is provided with a bearing 28 at its outer end that also supports the torsion spring 19. In the embodiment of FIG. 2 the torsion spring consists of a first inner tubular member 29 that extends into the barrel casing 12 and is supported by the

bearing 28. The free end 30 of the first tubular member 29 extending outside the barrel casing 12 is held rigidly by some suitable means. As shown in FIG. 2, I prefer to hold the tube 29 near its end 30 by means of a tension wheel 31 which has a series of circumferentially spaced apart lugs 32 each with a radial opening 33. The wheel 31 can then be rotated to place an initial twist and thus store torsional energy in the spring motor 19 with the door in the up position. When the wheel 31 has been turned initially the desired amount, the nearest opening 33 can be aligned with an opening 34 in a fixed bracket 35 that is fixed to the wall or to a bracket 15 adjacent the wheel 31. A removable pin 36 then can be inserted through the aligned openings 33 and 34 to hold the wheel 31 in position. Other suitable means could also be used for holding the free end 30 of the inner tubular member 29 in a fixed position within the scope of the invention.

The inner tubular member 29, held tightly as its outside end 30 extends axially within the barrel casing 12 and is fixed at its opposite end 37 to a second larger coaxial tubular member 38. The tubular member 38 has a relatively short necked-down end portion 39 that fits tightly around the end of the inner tubular member 29. The two members 29 and 38 may be held together at this end connection by any suitable means that prevents relative movement between them at this location. As shown in the drawing a U-shaped clamp 40 may be utilized for this purpose, but in most instances it is preferable to weld the torque tubes 29 and 38 together. At their joined together ends 41, the members 29 and 38 are rotatably supported within the cavity 25 by the bearing 26. Except at the end connection 41 of the outer tube 38 is considerably larger and therefore does not touch or interfere with the inner coaxial tube 29. At its other end the outer tube 38 is affixed to the inner side of the hub member 22 by means of a sleeve member 42 that is held to the end of the tube 38 by a pair of clamps 43 or by welding, if desired.

In solving the problem of providing a smooth operating rolling door drive mechanism 10 I have discovered that certain materials provide more beneficial characteristics. For example, it is preferred that the torque tubes be preferably made of a strong, resilient form of steel with good elastic properties, such as a heat treated high carbon steel. A feature of my invention is that, in using metal tubes for supplying the torsional energy to operate a rolling door, a strong, positive but smooth operating force can be provided, and the operating characteristics of the drive mechanism, such as the amount of wind-up per force exerted can be readily tailored for a certain door size and weight by using tubes with particular lengths and wall thicknesses.

As shown in the embodiment of FIG. 5, more than two coaxial torque tubes can be utilized if desired to provide the force and operating characteristics required. In FIG. 5, the barrel mechanism 10a has end hub members 21a and 22a and an inner torque tube 29a that is fixed at one end outside the barrel 12a and is connected to a second tube 38a which in turn is connected to a third tube 45 and a fourth tube 46 at alternate ends with the fourth tube being affixed by means of a sleeve 47 to the hub 22a. In this embodiment the tubes are shown connected by welding. To prevent any unnecessary friction or interference between the concentric tubes, a suitable bearing member 48 is provided between the end connection of the tubes 38a and 45 and the inner tube 29a. Similarly, a bearing support 49 is provided between the end connection of the tubes 45 and 46 and the tubes 38a. The resulting torsion spring provided by the connected tubes 29a, 38a, 45 and 46 is equivalent to a single tube having almost four times the length of the barrel 12a. The overall effect of a longer torque tube is to increase the amount of wind-up that can be afforded to the barrel 12a and thus the length of door that can be rolled on the barrel. Within the practical limits of barrel diameter any num-

ber of connected torque tubes can be utilized within the scope of the invention.

FIGS. 6-8 show an installation for a flexible door 50 comprising a plurality of individual members 51 that are hinged together longitudinally. The ends of the members 51 are provided with rollers 52 (FIG. 8) which are adapted to ride in channel shaped tracks 53. The tracks 53 extend upward from opposite sides of the door opening 54 and curve inwardly above it to provide the storage position for the door in the opening position.

The embodiment shown in FIGS. 6-8 illustrates the versatility of the barrel drive mechanism 10b embodying the principles of my invention. In this arrangement the barrel housing 12b is supported by hanging brackets 15b in the aforesaid manner and is also provided with both a gear wheel 17b and a torque wheel 31b. However, fixedly mounted on the barrel near its opposite ends are a pair of drums or large sheaves 54. A pair of flexible cables 55 are each tied at one of their ends to the drums 54 and at their other end by a bracket 56 to the lowermost members 51 of flexible door 50. Thus, when the door 50 is to be raised the torsional energy stored in the barrel mechanism 10b by the end connected concentric tubes as shown in FIGS. 2-5 drives the drums to pull the door 50 upward with its rollers 52 guiding through the tracks 53.

From the foregoing, the operation of my improved rolling door mechanism should be apparent. However, in summary, with reference to FIGS. 1 and 2, the free end 30 of the torsion spring 19 extending from the barrel casing 12 is first rotated by means such as the torque wheel 31 to supply some initial twist and thus an amount of potential torsional energy in the barrel mechanism 10 which is sufficient to hold the rolled up door 11 in place. When the door 11 is to be lowered, the barrel is rotated by the chain 18 which turns the gear wheel 17. This rotation provides additional twist to the torsion spring 19, namely, the connected tubes 29 and 38 (FIG. 2). Thus, when the chain 18 is released and pulled in the opposite direction the door 11 will rise easily and rewind itself around the barrel 12. Because of the torque tube arrangement the operation is smooth, yet positive and will remain so over a long period of use due to the lack of fatigue and the inherent elasticity properties of the metal torque tubes, the lack of friction, and the elimination of thrust force components in my mechanism.

To those skilled in the art to which this invention relates, many changes in construction and widely differing embodiments and applications of the invention will suggest themselves without departing from the spirit and scope of the invention. The disclosures and the description herein are purely illustrative and are not intended to be in any sense limiting.

I claim:

1. In a drive mechanism for a vertically opening door, the combination comprising:
  - a barrel casing connected to the door and adapted to raise or lower it when said barrel casing rotates;
  - a pair of hub members fixed at opposite ends of said barrel casing;
  - a plurality of concentric radially spaced apart torsionally elastic tubes within said barrel casing including an innermost tube having one end extending axially outside said barrel casing and an outermost tube completely within said barrel casing, said outermost tube being fixed at one end to one of said hub members within said barrel;
  - each of said tubes being connected to their adjacent inner and outer tubes at one end, thereby forming a continuous segmented tube within said barrel casing and having an effective length substantially greater than that of said barrel casing;
  - a first bearing means in one of said hub members for

supporting the innermost tube and the adjacent tube connected thereto;

a second bearing means in the other said hub member for supporting said innermost tube near its end extending outside said barrel casing;

and means adjacent said barrel casing for holding the end of said innermost tube outside said barrel in a fixed predetermined position;

whereby all of said connected tubes will twist and store potential torsional energy when said barrel casing is rotated as the door is lowered and thereby provide driving power for opening the door when the energy is released.

2. In a drive mechanism for a vertically opening rolling door, the combination comprising:

a barrel casing attached to one end of the door and adapted to raise or lower it when said barrel casing rotates;

a pair of hub members fixed at opposite ends of said barrel casing;

a plurality of concentric metal torsion tubes within said barrel casing including an innermost tube having one end extending axially outside said barrel casing and an outermost tube completely within said barrel casing, all said tubes being engaged with an adjacent tube only at a limited connection area at one end and being otherwise spaced outwardly and thereby providing clearance with the adjoining tube, said outermost tube being fixed at one end to one of said hub members within said barrel;

each of said tubes being connected to their adjacent inner and outer tubes at one end, thereby forming a continuous segmented tube within said barrel casing that has an effective length substantially greater than that of said barrel casing;

a first bearing means in one of said hub members for supporting the innermost tube and the adjacent tube connected thereto;

a second bearing means in the other said hub member for supporting said innermost tube near its end extending outside said barrel casing;

and means adjacent said barrel casing for holding the end of said innermost tube outside said barrel in a fixed predetermined position;

whereby all of said connected tubes will twist and store potential torsional energy when said barrel casing is rotated as the door is lowered.

3. In a drive mechanism for a vertically opening door, the combination comprising:

a barrel casing connected to the door and adapted to raise or lower it when said barrel casing rotates;

a pair of hub members fixed at opposite ends of said barrel casing;

a plurality of concentric metal torsion tubes within said barrel casing including an innermost tube having one end extending axially outside said barrel casing and an outermost tube completely within said barrel casing, said outermost tube being fixed at one end within said barrel;

each of said tubes except said innermost tube having a necked-down portion at one end adapted to fit tightly around the adjacent inner tube, said tubes being connected to their adjacent inner and outer tubes at one end, thereby forming a continuous segmented tube within said barrel casing that has an effective length substantially greater than that of said barrel casing;

a first bearing means in one of said hub members for supporting the innermost tube and the necked-down end portion of the adjacent tube connected thereto;

a second bearing means in the other said hub member for supporting said innermost tube near its end extending outside said barrel casing;

and means adjacent said barrel casing for holding the

end of said innermost tube outside said barrel in a fixed predetermined position;

whereby all of said connected tubes will twist and store potential torsional energy when said barrel casing is rotated as the door is lowered.

4. In a drive mechanism for a vertically opening door, the combination comprising:

a barrel casing connected to the door and adapted to raise or lower it when said barrel casing rotates;

a pair of hub members fixed within said barrel casing at opposite ends thereof;

a pair of concentric metal torsion tubes connected together within said barrel casing including an innermost tube having one end extending axially outside said barrel and an outermost tube completely within said barrel casing, said outermost tube having a necked down end portion connected to said innermost tube and being fixed at its other end to a said hub member within said barrel;

one of said hub members having a bore providing bearing means for supporting said innermost tube with said barrel casing, and the other said hub member having a central axially aligned cavity for supporting the necked down end portion of said outermost tube and the connected innermost tube;

and means adjacent said barrel casing for holding the end of said innermost tube outside said barrel in a fixed predetermined position;

whereby said connected tubes will twist and store potential torsional energy when said barrel casing is rotated as the door is lowered and will provide driving power for opening the door when the stored energy is released.

5. In a drive mechanism for a vertically opening door, the combination comprising:

a barrel casing connected to the door and adapted to raise or lower it when said barrel casing rotates;

a plurality of interconnected concentric metal torsion tubes within said barrel casing including an innermost tube having one end extending axially outside said barrel casing and an outermost tube completely within said barrel casing, said outermost tube being fixed at one end within said barrel;

all of said tubes except said innermost tube having a necked down end portion, and means for connecting each of said tubes to their adjacent inner and outer tubes at a necked down end portion on one end, thereby forming a continuous segmented tube within said barrel casing having an effective length substantially greater than that of said barrel casing;

and means adjacent said barrel casing for holding the end of said innermost tube outside said barrel in a fixed predetermined position;

whereby all of said connected tubes will twist and store potential torsional energy when said barrel casing is rotated as the door is lowered and thereby provide driving power for opening the door when the energy is released.

6. The driving mechanism as described in claim 5 including annular means mounted between said concentric tubes within said barrel casing for preventing engagement between adjacent tubes during actuation of the mechanism.
